UNITED STATES PATENT OFFICE.

MAGNUS OLSON, OF GOLDEN, BRITISH COLUMBIA, CANADA.

CUTTER-HEAD.

1,308,297.

Specification of Letters Patent.

Patented July 1, 1919.

Application filed October 14, 1918. Serial No. 258,067.

To all whom it may concern:

Be it known that I, MAGNUS OLSON, a subject of the King of Great Britain, residing at Golden, in the Province of British Columbia and Dominion of Canada, have invented 5 new and useful Improvements in Cutter-Heads, of which the following is a specification.

This invention relates to cutter heads, particularly designed for cutting beveled surfaces such as ends of barrel staves, well curbing, or analogous articles, an object of 10 the invention being to provide a rotary cutter head, into which the blade or knife carrying block may be adjusted to cut square 15 surfaces or beveled surfaces of various angles.

More specifically, the invention comprehends the provision of a rotary cutter head 20 as specified including a plurality of blade carrying blocks, which are held connected to the body of the head by suitable wedge blocks and interlocking rib and recess structures, and an adjustable knife block adjusting member which may be moved, for varying 25 the angle of the outer surfaces of the knife carrying block, and consequently of the knives, for regulating the bevel of the surface being cut.

30 Other objects of the invention will appear in the following detailed description, taken in connection with the accompanying drawings, forming a part of this specification, and in which drawings:

35 Figure 1 is a side elevation of the improved cutter head.

Fig. 2 is an end elevation of the cutter head.

Fig. 3 is a longitudinal section through 40 the cutter head, taken on the line 3-3 of Fig. 2.

Fig. 4 is a detail perspective view of the knife block adjusting member and

45 Fig. 5 is a detail perspective view of one of the wedge blocks used in construction of the cutter head.

Referring more particularly to the drawings, 1 indicates the shaft which carries the cutter head. The cutter head proper comprises the main body 2, which is circular in shape and has a longitudinally extending sleeve 3 formed integrally therewith which sleeve is keyed by keys 4 to the shaft 1. The main body 2 of the cutter head is provided 50 with a plurality of diametrically opposed substantially rectangular openings 5 which

receive therein the cutter or knife carrying blocks 6. The blocks 6 are provided with laterally extending recesses 7 in their lower outer corners the edges of which recesses 60 are disposed at obtuse angles to each other, the side 8 being adapted to fit snugly against the inner inclined sides 9 of ribs 10 which extend across the outer end of the recesses 5, for connecting the blocks 6 to the main body 65 2 of the head to permit the blocks to be swung outwardly upon the inner edges of the ribs 9 as a pivot, and as indicated in dotted lines in Fig. 3 of the drawings, for regulating the angle of the outer surface of 70 the blocks and consequently regulating the bevel of the surface being cut by the cutter head.

The blocks 6 are held properly within the recesses 5 by wedge blocks 11 the outer surfaces of which are shaped to conform to the curvature of the circumference of periphery of the main body 2. The wedge blocks 11 have threaded shanks 12 formed thereupon upon which are mounted nuts 13. These 75 nuts 13 engage the outer surfaces of lugs 14 formed upon the outer surface of the body 2 for holding the wedges in adjusted positions and for drawing them inwardly into the portions of the recesses 5 upon one side of 80 each of the blocks 6 for securely wedging the blocks in the recesses and holding the blocks against longitudinal movement.

The knife blocks 6 are provided with angularly disposed recesses 15 which are 90 adapted to receive the cutters or knives, (not shown) and these recesses 15 have one of their sides inclined as clearly shown in Fig. 1 of the drawings for receiving therein the knife wedging blocks 16. The knife wedging blocks 16 have flat knife engaging surfaces 7 and their backs are provided with longitudinally extending ribs 18 which reinforce the block structures and merge into the threaded shank 19 formed upon the ends of 95 the wedging members or block 16. Nuts 20 are mounted upon the shank 19 and engage against the rear or inner ends of the heads 6 for drawing the blocks 16 into the recesses 15 to securely clamp a cutter or knife in each 100 of the recesses.

The sleeve 3 which is formed upon the main body 2 of the cutter head is provided with an angular channel 21 which receives therein set or lock screws 22. The set or lock 110 screws 22 extend through the threaded sleeve 23, connecting this sleeve against longitudi-

nal movement upon the sleeve 3. The outer threaded surface of the sleeve 23 engages in the threaded bore 24 of the knife carrying block adjusting head 25. The head 25 comprises a disk like body 26 having a plurality of substantially triangular shaped lugs 27 formed thereon at spaced intervals. The altitude or inclined sides of these substantially right angularly triangled lugs 27 is positioned outwardly and their apexes are adapted for engagement between the rounded inner lower edges 28 of the knife carrying blocks 6 so that when the adjusting member 25 is moved along the threaded sleeve 23, in the direction indicated by the arrow A in Fig. 3 of the drawings, the lugs will be wedged or forced beneath the blocks 6 rocking the blocks upon engagement between the blocks and the ribs 10, causing the blocks to be projected at various angles to the longitudinal axis of the cutter head for cutting surfaces of various beveled angles on the article being worked upon. Thus by moving the head 25 longitudinally along the threaded sleeve 23, the blocks 6 may be forced outwardly at greater angles to the axis of the head or allowed to move inwardly for decreasing the angle of the knife carried by the blocks with respect to the axis of rotation of the head and if the lugs 27 are withdrawn completely from beneath the inner flat surfaces of the blocks 6, a square surface may be cut on the article being worked upon.

Changes in detail may be made without departing from the spirit of this invention, but;

I claim:

1. In a rotary cutter head, the combination, of a body provided with a plurality of circumferentially spaced recesses, a plurality of knife carrying blocks pivotally seated in said recesses, means for adjusting the longitudinal angle of said block, comprising substantially triangularly shaped lugs for engagement with the inner surface of the block and for facial engagement with the inner wall of the recess to provide a firm support for the blocks.

2. In a rotary cutter head, the combination, of a body provided with a plurality of circumferentially spaced recesses, a plurality of knife carrying blocks pivotally seated in said recesses, a sleeve formed upon said body, a threaded sleeve carried by said first sleeve, a head adjustably carried by said threaded sleeve, substantially triangularly shaped lugs carried by said head for engagement with the inner surfaces of the blocks and for facial engagement with the inner walls of the recess to provide a firm support for the block.

3. In a rotary cutter head, the combination, of a main body provided with a plurality of recesses extending inwardly from

the periphery of the body, ribs formed upon said body and presenting inclined surfaces into said recesses, knife carrying blocks positioned in said recesses and having their inner forward corners cut away to fit said ribs and permit limited pivotal movement of the block with respect to said head. 70

4. In a rotary cutter head, the combination of a main body provided with a plurality of recesses extending inwardly from the periphery of the body, ribs formed upon said body and presenting inclined surfaces into said recesses, knife carrying blocks positioned in said recesses and having their inner forward corners cut away to fit said ribs and 75 permit limited pivotal movement of the block with respect to said head, and means adjustably carried by said body and adapted to engage beneath the blocks at their ends opposite said cut out portion to vary the angle of the outer surfaces of the block with 80 respect to the axis of rotation of the cutter head. 85

5. In a rotary cutter head, the combination, of a main body provided with a plurality of recesses extending inwardly from the periphery of the body, ribs formed upon said body and presenting inclined surfaces into said recesses, knife carrying blocks positioned in said recesses, and having their inner forward corners cut away to fit said ribs and permit limited pivotal movement of the block with respect to said head, means adjustably carried by said body and adapted to engage beneath the blocks at their ends opposite said cut out portion to vary 90 the angle of the outer surfaces of the block with respect to the axis of rotation of the cutter head. 95

6. In a rotary cutter head, the combination, of a main body provided with a plurality of recesses extending inwardly from the periphery thereof, a plurality of knife carrying blocks mounted in said recesses and adapted for pivotal movement with respect to the main body, a threaded sleeve formed upon said main body, a head adjustably carried by said sleeve, lugs formed 105 upon said disk and adapted to engage beneath said knife carrying blocks to pivotally move the blocks to vary the angle of the outer surfaces of the blocks with respect to the axis of rotation of the head. 110

7. In a rotary cutter head, the combination, of a main supporting body provided with a plurality of recesses extending inwardly from the periphery thereof, knife carrying blocks mounted in said recesses, 120

means for preventing longitudinal movement of said blocks within said recesses, a sleeve formed upon said main body, an adjusting head carried by said sleeve, a plurality of lugs carried by said adjusting head and adapted to engage beneath said knife carrying blocks to move the blocks in said recesses to vary the angle of the outer surfaces of the blocks with respect to the axis 10 of rotation of the head.

8. In a rotary cutter head, the combination, of a main body, provided with a plurality of recesses extending inwardly from the periphery of the body, ribs extending 15 across the outer ends of said body and having their inner edges beveled, knife carrying blocks mounted in said recesses and having their outer lower corners cut away to receive said ribs and permit limited pivotal 20 movement of the blocks with respect to the body, a sleeve formed upon said body, an adjusting head adjustably carried by said sleeve, substantially triangularly shaped lugs formed upon said adjusting head and 25 adapted to engage beneath the inner sur-

faces of said knife carrying blocks to pivotally move the block within said recesses.

9. In a rotary cutter head, the combination, of a main body, provided with a plurality of recesses extending inwardly from the periphery of the body, ribs extending 30 across the outer ends of said body and having their inner edges beveled, knife carrying blocks mounted in said recesses and having their outer lower corners cut away to 35 receive said ribs and permit limited pivotal movement of the blocks with respect to the body, a sleeve formed upon said body, an adjusting head adjustably carried by said sleeve, substantially triangularly shaped 40 lugs formed upon said adjusting head and adapted to engage beneath the inner surfaces of said knife carrying blocks to pivotally move the blocks within said recesses, wedge members carried by said main body 45 and engaging one side of said knife carrying blocks, and means for forcing said wedge members into engagement with the adjacent sides of the knife carrying block.

MAGNUS OLSON.
